GAME APPARATUS

Loren E. Johnson and Benedict C. Bordonaro,
Olean, N. Y.

Application January 25, 1937, Serial No. 122,282

1 Claim. (Cl. 273—142)

This invention relates to a game apparatus and, more particularly, relates to a chance controlled device for determining the winner of a prize offered as an inducement to encourage more frequent patronage for theaters. The game is part of a plan or method which is carried out in the form of a dramatic skit or playlet in which the audience takes part.

The plan comprises awarding a prize to a patron of the particular theater or motion picture house visited on the occasion that the plan is in operation. It is an object of the plan to choose, by means of the apparatus hereinafter described, a month and date of the year, and to award a prize to the person or persons present in the audience whose birthday happens to fall on the date chosen by means of this apparatus. The apparatus also provides means for determining whether the recipient of the award shall be male or female.

An embodiment of the invention is illustrated in the accompanying drawing, in which like reference characters refer to like parts in the several figures.

In this drawing,

Figure 1 is a front elevation of the device;

Figure 2 is a side elevation thereof, with a portion of the base broken away;

Figure 3 is an enlarged sectional detail along line 3—3 of Figure 1.

The apparatus consists of a suitable base 1 which supports a vertical standard 2. At a suitable point this standard is transfixated by a bolt or shaft 3, secured thereto by any desirable means, such as a nut 4 and collar 5. Rotatably mounted on this shaft are a series of concentric discs or dials 6, 7, and 8 which are spaced from each other by means of spacing collars 9 which are suitably pinned to the shaft 3. These dials increase progressively in diameter in the order named so as to leave visible a marginal portion of the last two. Adjacent the periphery of each of these dials a series of equidistantly spaced pins 10 are secured in any suitable manner around the marginal portions thereof but are preferably arranged midway between the dividing lines of the parts hereinafter referred to. The marginal portion of the largest disk 8 is divided into twelve equal parts which are designated by the names of the months of the year. The next smaller and adjacent disk 7 is likewise divided into a number of equal parts which bear as visible indicia the numbers of the days of a month, consecutively arranged. The smallest and foremost disk is also divided into a number of equal portions which are inscribed with the notation "male", "female" occurring alternately around

the entire face of the disk adjacent the periphery thereof.

The standard 2, at a point above the uppermost portion of the disk 8, has an arm 11 extending therefrom parallel to the shaft 3. From this arm, flexible spring fingers 12, suitably spaced, extend downwardly, each engaging the pins 10 of one of the disks 6, 7 and 8. The device is preferably made in a large size, about the height of a man, so that it may be viewed on the stage from all portions of the house.

In use, one or more members of the audience may be invited up to the stage to operate the device. The disks may be rotated by grasping one of the pins 10 and giving the wheel a quick spin as will be obvious from the construction. The disks may be rotated simultaneously or independently, although it will be obvious that the enjoyment of the audience will be enhanced by the element of suspense present when the disks are rotated in series.

The plan or method is suitably dramatized at each performance, and the dramatization may be different for successive performances, as desired, or the same skit may be re-enacted for subsequent performances of the same attraction since the performers will not be the same if chosen from the audience.

It will be understood that the choice of a winner is made when all of the disks have been rotated and allowed to come to a stop, the flexible fingers 12 exerting a braking influence. The name of the month appearing at the top of the device, and the date and sex indicated on the top of the adjacent disks and in vertical alignment with the month designates the winning combination, and the person or persons in the audience whose birthday falls on that date may claim the prize. In the event that more than one claimant appears, the prize may be duplicated, and if no claimant appears for that particular performance, the prizes may be permitted to accumulate for the next performance.

Having thus described our method and apparatus, we claim:

A game apparatus for selecting a prize winner according to date of birth and sex which comprises a base, a standard supported thereon, a shaft projecting therefrom, dials mounted on said shaft, said dials being individually, independently and selectively rotatable thereon, means for individually and independently stopping the rotation of each dial and indicia carried by said dials so arranged as to indicate a month, date and sex adjacent said stopping means when said dials come to rest.
